US00D459217S

(12) **United States Design Patent** (10) Patent No.: **US D459,217 S**
Puglisi (45) Date of Patent: ** *Jun. 25, 2002

(54) **CONTAINER**

(75) Inventor: **Salvatore A. Puglisi**, Wayne, NJ (US)
(73) Assignee: **Warner-Lambert Company**, Morris Plains, NJ (US)
(*) Notice: This patent is subject to a terminal disclaimer.
(**) Term: **14 Years**
(21) Appl. No.: **29/056,772**
(22) Filed: **Jul. 9, 1996**
(51) LOC (7) Cl. **09-03**
(52) U.S. Cl. **D9/339**
(58) Field of Search D9/339, 414, 420, D9/423, 432; D3/294; 221/154, 281, 303, 305, 306
